CLAIM

The ornamental design for a pair of side mirrors for a vehicle, as shown and described.

DESCRIPTION

This application is related to the following co-pending applications:

Application Ser. No. 29/290,522 entitled “Side Mirror for a Vehicle”; and

Application Ser. No. 29/290,521 entitled “Foot for a Side Mirror for a Vehicle”.

FIG. 1 is a rear perspective view of a first embodiment of a pair of side mirrors for a vehicle according to our novel design;

FIG. 2 is a rear view thereof;

FIG. 3 is a side view thereof;

FIG. 4 is a front view thereof;

FIG. 5 is a top view thereof; and

FIG. 6 is a bottom view thereof.

FIG. 7 is a rear perspective view of a second embodiment of the pair of side mirrors for a vehicle according to our novel design;

FIG. 8 is a rear view thereof;

FIG. 9 is a side view thereof;

FIG. 10 is a front view thereof;

FIG. 11 is a top view thereof; and,

FIG. 12 is a bottom view thereof.

The broken lines are for illustrative purposes only and form no part of the claimed design.
